(57) **CLAIM**

The ornamental design for an absorbent article, as shown and described.

DESCRIPTION

FIG. 1 is a front elevation view of an absorbent article showing one embodiment of my new design;

FIG. 2 is a rear elevation view thereof;

FIG. 3 is a right side view thereof;

FIG. 4 is a left side view thereof;

FIG. 5 is a top plan view thereof; and

FIG. 6 is a bottom plan view thereof.

FIG. 7 is a front elevation view of an absorbent article showing another embodiment of my new design;

FIG. 8 is a rear elevation view thereof;

FIG. 9 is a right side view thereof;

FIG. 10 is a left side view thereof; and,

FIG. 11 is a top plan view thereof.

The broken dash lines in the figures depict portions of the absorbent article that form no part of the claimed design, e.g., such broken dash lines show the general environment of the product on which the design is applied.
